UNITED STATES PATENT OFFICE

2,430,110

APPARATUS FOR COOLING AIR BY LIQUID
CONTACTJohn A. De Vilbiss, St. Marys, Kans., assignor
to Rockhurst College, Kansas City, Mo., a cor-
poration of Missouri

Application April 23, 1945, Serial No. 589,727

1 Claim. (Cl. 62—95)

1

This invention relates to air conditioning means for closed spaces, such as rooms, walk-in refrigerators, storage compartments, and, in fact, any space created by circumscribing walls, a floor and a ceiling.

The primary aim of this invention is to provide conditioning means for closed spaces, which means may be built as an integral part of the structure, or added thereto through suitable installation methods after the closed space or compartment has been in use for a period of time.

One of the important objects of my invention is to provide means for conditioning the air within a closed space, which means includes the necessary elements for establishing a natural movement of air currents, which currents travel across the surface of a liquid wherein cooling coils are submerged.

This invention has for further objects the provision of air conditioning means for spaces of the aforementioned type and character, that includes an open top reservoir, disposed near the ceiling of the closed space; a filling of liquid in the reservoir; and a cooling coil submerged within the liquid.

The particular form and size of the open top reservoir is important and therefore, constitutes one of the main features of this invention. The manner of maintaining the liquid in said reservoir at a predetermined level is also an element of the conditioning means and all of the aforementioned parts combine to produce a simple, efficient and relatively inexpensive system for conditioning enclosed spaces.

Other objects of the invention will appear during the course of the following specification, referring to the accompanying drawing wherein:

Fig. 1 is an elevational-sectional view of a cabinet having its space conditioned through structure made in accordance with the present invention; and

Fig. 2 is a horizontal sectional view taken on line II—II of Fig. 1 and looking in the direction of the arrows.

While I have chosen a refrigerator as the unit having an enclosed space 10 therein, it is obvious that the air conditioning means soon to be described, may be installed in any space enclosed by suitably insulated walls.

The cabinet 12 of the illustrated refrigerator, includes walls 14, a top 16, a door 18, and a floor 20. Thus, space 10 is established and the means for conditioning the air in that space may be supported near the top thereof and immediately below the inner surface 22 of top 16.

2 The air conditioning means comprises a relatively shallow pan 24 having a sheet of insulating material 26 across the bottom and an open top defined by upstanding walls 28. A well 30 is formed through pan 24 near its center and the vertical flanges 32 circumscribing this well 30, cooperate with walls 28 in producing a shallow reservoir or pan 24 wherein is contained a filling of liquid 34.

10 A conduit 36 trapped as at 38, extends to a point exterior of space 10 and the vertical branches 40 terminate on a horizontal plane where the level of liquid 34 is to be established. Pan 24 is mounted upon brackets 42 secured to 15 the side walls 14, or, any other means for suspending pan 24 may be employed so long as the space 44 between the perimeter of pan 24 and the inner faces of walls 14 is not restricted.

As illustrated in Fig. 1, the reservoir or open 20 top pan 24 should be placed relatively close to the upper surface 22 and the size of this pan 24 should be such as to establish a continuous space 44 through which the air currents may pass as they move upwardly along the inner surfaces of 25 walls 14, across the surface of liquid 34, and thence downwardly through well 30. The direction of travel is indicated by the arrows illustrated in Fig. 1, and when this action of the air in space 10 takes place, a desired heat exchange occurs 30 without experiencing a "frosting" of any part of the system.

Cooling coils 46 are submerged in filling of liquid 34 and these continuous coils 46 are connected to means not here shown for supplying 35 a refrigerant thereto, all as is well known in the art.

The action of the cooling coils 46 will maintain 40 a relatively low temperature in that portion of space 10 above pan 24 and the tendency of the cooler air to pass downwardly through well 30, will establish a movement of air that would draw the relatively warm air upwardly through space 44 at the edge of pan 24. The theory upon which the conditioning means above described is predicated is believed to be sound, for observations 45 have taught that not only will the air circulate as described, but moisture will be withdrawn therefrom and collected in pan 24. If the liquid level tends to rise, then the overflow pipe 36 will 50 function.

Frosting of cooling coils 46 is entirely eliminated due to the manner of submerging said coils in liquid 34. Loss of efficiency therefore, which is normally due to frosting, is not experienced 55 when the air conditioner disclosed above is em-

ployed and long periods of operation may therefore, take place without maintenance of any type.

Liquid 34 may be brine or such substance as will not freeze at a low temperature. When such liquid is used the cooling coils 46 will not solidify liquid 34 and, therefore, the action of the apparatus will always be such as to obtain the full efficiency of the cooling coils.

The open top pan or reservoir 24 has been illustrated as constituting a single unitary, shallow member but a plurality of shallow trays may be employed if desired.

Space 10 is illustrated in Fig. 1 as being divided into two parts by a partition wall 48 through which passages 50 are created to insure adequate circulation of air. The insulation 26 along the bottom of pan 24 should be effective enough to preclude cooling of the air adjacent to the bottom of pan 24 by the liquid or coils 34 and 46 respectively, and when this insulation is so placed, the movement of air above described and indicated by the arrows will always occur.

Since the space air conditioner embodying my invention might be made to present different capacities, and further, in view of the fact that it may be installed wherever an enclosed space is to be treated, it is desired to be limited only by the spirit of the invention and scope of the appended claim.

Having thus described the invention, what is claimed as new and desired to be secured by Letters Patent is:

Air conditioning means for a closed space comprising an open top, horizontally disposed pan near the top of the space, said pan being smaller than the horizontal cross sectional area of the space being conditioned to present marginal passages for upwardly moving, warm air within the space, said pan being adapted to contain a filling of liquid having a low freezing point to be traversed by air that has moved through said 5 passages; a refrigerating coil in the pan at least partially submerged by the liquid, said pan having an opening substantially centrally there-through to present a passage for downwardly moving air that has been cooled by traversing 10 said liquid; a conduit in communication with the pan for maintaining the liquid at a predetermined level as moisture from the air is deposited in the pan; and a covering of insulating material for the bottom of the pan for preventing 15 cooling of air below said pan.
